CIRCULAR LOOM

William Pool, Spondon, near Derby, England, assignor to Celanese Corporation of America, a corporation of Delaware

Application January 3, 1936, Serial No. 57,391
In Great Britain January 16, 1935

6 Claims. (Cl. 139—13)

This invention relates to circular looms, and particularly to the shuttles and weft supplies of such looms.

According to the invention, the weft spool of a circular loom is arranged to rotate to permit weft to be withdrawn by rotation of the spool, and a brake member is movably mounted in proximity to the spool, so that when the shuttle carrying the spool ceases to rotate, the inertia of the 10 brake member causes the member to move, and thereupon to apply a braking force to the spool to check its rotation. In this way over-running of the spool with consequent unwinding of weft is avoided, so that the spool is immediately ready 15 for use on re-starting of the loom.

The brake member is preferably arranged as a lever provided with considerable leverage, a brake pad for engagement with the spool being placed near to the pivot of the lever, while the 20 mass of the lever (including, if desired, additional weight provided to load the lever) is several times farther away from the pivot. Such a lever gives a relatively powerful braking action, and rapidly brings the spool to rest. When the deceleration 25 ceases, the brake automatically moves out of contact with the spool.

By way of example a form of braking apparatus according to the invention will now be described in greater detail with reference to the accompanying drawing in which:—

Fig. 1 is a side elevation of the braking apparatus incorporated in a circular loom shuttle of the same general type as that described in U. S. application S. No. 43,539 filed 4th October 1935.

Fig. 2 is a part cross-sectional end elevation viewed along line 2—2 of Fig. 1 with the spool shown in dotted lines; and

Fig. 3 is a view on larger scale of a detail of Fig. 1.

The shuttle comprises a top plate 3 and an intermediate plate 4, the two plates being connected by a rear plate 5 of sheet metal or like material. Depending from the intermediate plate 5 is the lower portion, or body, of the shuttle generally indicated by 6, the body 6 carrying two pairs of flanged rollers 7 for engagement by vane wheels 8, which position and drive the shuttle between the divided warp threads 9. For further details of the construction and operation of the shuttle 50 reference may be had to the specification previously referred to.

A shallow circular spool 10 freely rotatable about a spindle 11 outstanding from the rear plate 5 supplies weft thread 12 to the fell of the 55 fabric, the weft thread passing from the spool to

the fell of the fabric through guides 13. The spool 10 is rotated about the spindle 11 by the pull of the unwinding weft thread 12 as the shuttle is driven along its path round the loom.

The spool 10 is spaced from the rear plate 5 by a shoulder 15 formed on the spindle 11, the spool being retained on the spindle by a spring clip 16 fitting into a circumferential groove formed at the end of the spindle. The spring clip 16 allows of quick removal and replacement 10 of the spool 10.

Disposed in the space between the spool 10 and the rear plate 5, on the right-hand side of the spindle 11, is a lever 17, the lever being freely pivoted at its upper extremity on a bracket 18 and consequently capable of swinging pendulum-wise between the spool and the plate.

The lever 17 is provided with a weight 19 at its lower extremity and with a brake for the spool at a point near its upper extremity. The brake 20 comprises a lined shoe 21 outstanding from the lever 17, in the manner shown clearly in Figs. 2 and 3, the brake being just clear of the edge of the inner flange of the spool when the lever 17 is in vertical position.

The extent of the movement of the lever 17 is controlled by a strap 22 secured to the plate 5. So long as the shuttle is not decelerating the lever 17 either hangs vertically downwards or, if the shuttle is travelling very quickly, the inertia 30 of the lever and the weight 19 may cause the lower end of the lever to bear against the right-hand limit of the strap 22, the brake 21 in either case being clear of the spool 10.

When, however, the shuttle is stopped, the inertia of the lever 17 and weight 19 causes the lever to continue its forward motion parallel to the plane of rotation of the shuttle with the result that the lever swings to the left about its pivot and applies the brake 21 to the inner flange of 40 the spool 10, the spool thus being brought to rest substantially simultaneously with, or very quickly after, the stoppage of the shuttle. In this manner, over-running of the spool, with consequent undesirable unwinding of the weft thread 12, 45 is prevented. The operative or braking position of the lever 17 is shown in dotted lines in Fig. 1.

When the deceleration of the shuttle ceases, the lever 17 swings to the right automatically and removes the brake 21 from contact with 50 the spool, in readiness for re-starting of the loom.

The force of the application of the brake 21 is substantially proportional to the rate of deceleration of the shuttle and depends on the 55

mass of the weight 19 and the leverage provided by the lever 17. The weight 19 may be replaced by one of greater or less mass, or may be adjusted in position on the lever 17 nearer to or 5 farther from the pivot in accordance with the speed at which the shuttle is to run, and if necessary, with the weight of weft carried by the spool.

While the rate of rotation of the spool 10 increases as the amount of weft remaining on the spool becomes less, the energy to be absorbed in bringing the spool to rest is not materially changed, so that the brake 21 is substantially uniform in its action throughout the whole run 15 of the spool. Moreover, the reduction in the weight of the spool 10 tends to overcome the tendency for the weft tension to increase as the diameter decreases, so that weft tension likewise is maintained approximately constant.

20 While the invention has been described more particularly in connection with the application of a brake to the edge of a flange of the spool, it will be understood that the movement of the lever 17 could simply be adapted to apply a braking force to the spool 10 in many different ways. For example, the swinging of the lever could bring about the contraction of a brake band on 25 to a drum-portion formed on the spool, or the introduction of a braking wedge between the inner face of the spool and the rear plate 5 of the shuttle.

30 The weft spool arrangement above described is useful for weaving with low twist continuous filament weft since it effectively provides for uniform low weft tension. It is also very useful for weaving untwisted weft, and particularly weft-like metallic ribs or strips of artificial foils, since it enables these to be laid in the fabric without the insertion of any twist during unwinding.

35 40 Having described my invention, what I desire to secure by Letters Patent is:—

1. A circular loom shuttle adapted for propulsion round the loom, comprising means to support a weft spool rotatably in the shuttle, and 45 a freely movable braking member mounted in proximity to the spool and adapted, on deceleration of the shuttle, to move under the influence of inertia and thereupon to apply a braking force to the spool.

50 2. A circular loom shuttle adapted for propul-

sion round the loom, comprising means to support a flanged weft spool rotatably in the shuttle, and a freely movable braking member mounted in proximity to the spool and adapted, on deceleration of the shuttle, to move under the 5 influence of inertia and thereupon to apply a braking force to a flange of the spool.

3. A circular loom shuttle adapted for propulsion round the loom, comprising means to support a weft spool rotatably in the shuttle, a 10 pivot in the vicinity of the spool, and a spool-braking member freely mounted on said pivot and adapted on deceleration of the shuttle to rotate about said pivot under the influence of inertia and thereupon to apply a braking force to 15 the spool.

4. A circular loom shuttle adapted for propulsion round the loom, comprising means to support a weft spool rotatably in the shuttle, a pivot in the vicinity of the spool, a lever freely 20 mounted on said pivot, and a spool brake in association with said lever, said lever being adapted, on deceleration of the shuttle, to rotate about said pivot under the influence of inertia and thereupon to apply said brake to the spool. 25

5. A circular loom shuttle adapted for propulsion round the loom, comprising means to support a flanged weft spool rotatably in the shuttle, a pivot in the vicinity of the spool, a lever freely suspended from said pivot, and a 30 spool brake disposed on said lever in proximity to the edge of a flange of said spool, said lever being adapted, on deceleration of the shuttle, to rotate about said pivot under the influence of inertia and thereupon to apply said brake to a 35 flange of the spool.

6. A circular loom shuttle adapted for propulsion round the loom, comprising means to support a weft spool rotatably in the shuttle, a pivot in the vicinity of the spool, a lever freely 40 mounted on said pivot, a spool brake in association with said lever, said lever being adapted, on deceleration of the shuttle, to rotate about said pivot under the influence of inertia and thereupon to apply said brake to the spool, and 45 a weight on said lever, said weight being replaceable by a weight of different mass in accordance with the braking force desired.
